PRINTED TEXTILE FABRIC OR SIMILAR ARTICLE

John W. Rock, Wyckoff, N.J., assignor to Solinger and Sons Co., Inc., New York, N.Y., a corporation

Filed Aug. 17, 1960, Ser. No. 61,797

Term of patent 3½ years

(Cl. D92—1)

The figure is a plan view of a printed textile fabric or similar article showing my design. The dot and dash lines of the drawing outline a design unit, which unit is repeated in regular succession, as indicated by the extensions beyond the unit boundary.

I claim:

The ornamental design for a printed textile fabric or similar article, substantially as shown and described.
